WALTHER AKEMANN, OF ESSEN, GERMANY, ASSIGNOR TO FRIED. KRUPP AKTIEN-
GESELLSCHAFT, OF ESSEN-ON-THE-RUHR, GERMANY.

FIRE-CONTROL APPARATUS FOR NAVAL GUNS.

1,373,793.

Specification of Letters Patent.

Patented Apr. 5, 1921.

Application filed September 3, 1920. Serial No. 408,073.

To all whom it may concern:

Be it known that I, WALTHER AKEMANN, residing at Essen, Germany, a citizen of the German Republic, have invented a certain 5 new and useful Improvement in Fire-Control Apparatus for Naval Guns, of which the following is a specification.

This invention relates to that type of fire controlling apparatus particularly intended 10 for naval guns in which a gyroscopic apparatus is provided at the transmitting station for the purpose of taking into account the angle of advanced ignition which corresponds to the firing delay when the ship 15 is making rolling movements. The object of the invention is to provide a fire controlling apparatus of the kind above referred to which is of a very simple construction, is correspondingly simple to manipulate, and which enables the guns to be accurately adjusted when the ship is rolling or pitching. According to the present invention this object is attained owing to the fact that the arrangement for taking into 20 account the angle of advanced ignition corresponding to the firing delay, has two adjustable marks corresponding to the angle of rolling and two marks which enable a firing circuit to be closed, of which one pair 25 of marks are rigidly connected to a sighting telescope stabilizable by the gyroscope and the other pair of marks are connected to a common driving member so that as the said driving member rotates, the two marks 30 which enable the firing circuit to be closed are adjusted to that angle of advanced ignition which corresponds to the angle of rolling previously adjusted on the other two marks.

40 In order that the invention may be clearly understood reference is made to the accompanying drawing which shows diagrammatically a construction illustrating the subject matter of the invention.

45 The fire control apparatus consists of two separate arrangements which are connected by electrical conductors, of which one is situated at the controlling station and the other at the gun station. The arrangement situated at the controlling station consists of a casing A rotating about a vertical axis, from which is suspended by a Cardan suspension an electrically driven gyroscope B. The outermost of the two Cardan rings 50 of the gyroscope has two Cardan pins which

pass through the casing, one of said pins carries a pointer rigidly connected to it and extending downward and a horizontal telescope B². The gyroscope is provided for the purpose of maintaining the direction 60 imparted to the telescope B² when the ship rolls or pitches. The magnitude of the angle of rolling is read off on a scale a¹ graduated to indicate the rolling angle, mounted on the casing A and extending to 65 both sides thereof and an indicator, thread b⁴ stretched across a rectangular slot b³ in the pointer B¹. The pointer B¹ has also an indicator mark b⁵ and a firing tongue b⁶ mounted on its free end and the points of 70 the indicator mark b⁵ and the firing tongue b⁶ are in line with the indicator thread b⁴. The firing tongue b⁶ is provided for coöperating with a second firing tongue c¹ mounted on a sector piece C curved to the 75 arc of a circle and pivotally guided about the axis of the Cardan pins above mentioned. The sector piece C is reciprocated by means of a lever D which is connected thereto by a connecting rod d¹. The said 80 sector piece C is formed on its under side with teeth c² with which the teeth of a toothed wheel a² rotatably mounted on the casing A engage. The toothed wheel a² gears through the medium of toothed wheels 85 a³, a⁴, a⁵, a⁶ with the teeth e³ of a sector E which is pivotally mounted on the casing A to turn about the axis of the above mentioned Cardan pin. The toothed sector E has an indicator mark e¹ and an angle graduation which extends on both sides of this mark. The toothed sector E, positively connected to the lever D, by the mechanism d¹, C, c², a², a³, a⁴, a⁵, a⁶, e³, may be employed to follow the mark b⁵ with the mark 90 e¹ during the rolling of the ship and also the relative movements of the pointer B¹ with respect to the casing A which occur at the same time until the pointer B¹ and mark b⁵ have reached their greatest outward swing, 95 the lever D being then secured. The ratio of transmission between the lever D and the toothed sector E is such that the firing tongue c¹ mounted on the toothed sector C assumes, when the lever D is secured as 100 described at the instant of the greatest swing of the mark b⁵, an angular position with respect to the firing tongue b⁶ on the pointer B¹ which retains its position corresponding 105 to the firing delay, and corresponding to the 110

- angle of rolling indicated by the position of the mark b^5 or e^1 . The firing tongues b^6 and c^1 lie, as indicated in the drawing, in a circuit connected to a source of continuous current in which is also included a firing switch F situated at the controlling station and the exciting winding g^1 of the firing magnet (not shown) situated in the breech part of the gun barrel G.
- 10 At the controlling station is placed a transmitter H forming part of an electrical long distance controlling apparatus, having an indicating apparatus h^3 to enable range of the target to be adjusted, constructed on 15 the coarse and fine system. This transmitter serves to adjust a receiver H^1 also constructed on the coarse and fine system mounted on the gun, to the range of the target determined at the controlling station.
- 20 The transmitter H has also an indicating apparatus H^2 which enables any angle of pitching of the ship there may be and which is determined by the aid of the indicator apparatus b^4 , a^2 to be taken into account 25 when adjusting the receiver to the range of the target. Finally the elevating gear, by means of which the gun barrel G is adjusted to the elevation indicated by the receiver H^1 , is positively connected to a repeating transmitter J also constructed on 30 the coarse and fine system and the similarly constructed receiver J^1 situated at the controlling station and indicates to the man who operates the firing switch whether the gun barrel G has received the elevation 35 corresponding to the range of the target.
- For the consideration of the working of the above described fire controlling apparatus let it be assumed that the gun barrel 40 G and the casing A have been laterally adjusted to the target and the ship is executing rolling movements about its horizontal floating position while the firing switch F is open.
- 45 If the gun barrel G is to be adjusted by the aid of the above described fire controlling apparatus to the range of the target and fired, at an instant which is in advance, by the magnitude of the firing delay corresponding to the size of the angle of 50 rolling, of the instant when the ship passes through the horizontal floating position, the transmitter H situated at the controlling station is first adjusted to the range of the target by the aid of the indicating apparatus h^3 . The adjustment of the transmitter H results in a corresponding adjustment of the receiver situated at the gun station and on the indicating apparatus by 55 which the range of the target is consequently ascertainable. The gun barrel G is then adjusted to the elevation corresponding to the range of the target by the elevating gear. The adjustment of the gun barrel is also taken part in by the repeating 60

transmitter J situated at the gun station which transmits its adjustment to the receiver J^1 situated at the controlling station. By the agreement of the indications of the receiver J^1 and the indicating apparatus h^3 70 of the transmitter H, it can then be readily ascertained that the gun barrel G has the elevation imparted to it corresponding to the range of the target. As soon as this is found to be the case the lever D is rocked 75 by hand in order that the toothed sector E positively connected to it by the mechanism d^1 , C, c^2 , a^2 , a^3 , a^4 , a^5 , a^6 , e^3 , and the mark e^1 fixed thereon is kept in coincidence with the mark b^5 of the pointer B^1 , until it 80 has attained its greatest outward swing in respect of the scale a^4 indicating the rolling angle, mounted on the casing A, the lever D being then secured. The above described movement of the lever D is taken part in by 85 the toothed sector C with its firing tongue c^1 and it moves, when the ratios of transmission for the toothed sector C and the toothed sector E are those given, through an angle which just corresponds to the firing delay belonging to the position of the mark e^1 . If the firing switch be now closed 90 the projectile, as both firing tongues b^6 , c^1 are adjusted to the angle of advanced ignition which corresponds to the angle of 95 rolling, will leave the gun barrel at an instant which corresponds exactly to the firing delay. If it be found, for example, that in view of the position of the gun barrel G improvements in the angle of preliminary 100 ignition are necessary, the mark b^5 is not followed with the mark e^1 when the lever D is rocked but one of the adjacent small divisions of the angle graduation e^2 is used.

If it is found that the ship is making its 105 rolling movements not about its horizontal floating position but about a position of rest which differs from the horizontal by the angle of pitching $+\alpha$, the angle of pitching will be indicated, when the telescope B^2 is directed horizontally, on the indicator apparatus for the rolling angle and adjusted both on the apparatus H^2 for taking into account the influence of the angle of pitching to the necessary elevation of the 110 gun barrel G and also on the lever D for the purpose of correspondingly moving the firing tongue c^1 and the mark e^1 positively connected thereto. In other respects the manipulation of the fire controlling apparatus does not differ from that hereinbefore described.

The arrangement described differs from known fire control apparatus fitted with gyroscopic apparatus for adjusting the angle 115 of preliminary ignition, by its simple construction which avoids sensitive parts, and to this simple construction a correspondingly simple manipulation insures great accuracy in the adjustment and answers all the 120

requirements which must be made of a fire control apparatus for warships as regards its possibilities of use and its accuracy.

That great accuracy in the adjustment of 5 the angle of preliminary ignition combined with simplicity in construction is attainable with the fire controlling apparatus described, follows from the fact that the mark b^5 which is stabilized during the rolling 10 movements by the gyroscope can be easily followed with the hand adjustable mark and moreover the point of reversal of the stabilized mark b^5 can be determined when the rolling movements are severe with great accuracy 15 by means of the hand operated mark e^1 , as the relative speed of the stabilized mark with respect to the casing A at the instant of reversal is equal to zero in all cases.

Without making any change in the essential 20 features of the invention, the transmitter H might be so arranged that the adjustment of its movable part to the range of the target results directly in an elevation of the gun barrel G corresponding to this range of the 25 target.

Claims.

1. Fire control apparatus of the class described which comprises a sighting device, a stabilizing device for said sighting means, 30 a pair of marks adjustable to correspond to the angle of rolling of a ship, a pair of contact devices for closing a firing circuit, one of said marks and one of said contact devices being rigidly connected to the sighting 35 means and the other mark and contact device being operatively connected together and means for adjusting said mark and contact device.

2. An apparatus of the class described 40 which comprises a sighting telescope, a gyroscopic apparatus for stabilizing said telescope, an arm rigidly secured to said sighting device, a mark fixed upon said arm, a contact fixed upon said arm, a second mark 45 coöperating with said first mentioned mark, a second contact device coöperating with

said first mentioned contact device, means operatively connecting said second mark and second contact and means whereby they may be adjusted simultaneously and at a different 50 ratio of movement.

3. A fire control apparatus of the class described which comprises a stabilizable shaft, a gyroscopic apparatus for stabilizing said shaft, a sighting telescope carried by said 55 shaft, a pointer rigidly secured to said stabilizable shaft, a mark and a contact device rigidly attached to said pointer, a second mark coöperating with said first mentioned mark, a second contact device coöperating 60 with said first mentioned contact device, a pair of sectors arranged concentrically with the stabilizable shaft, said second mark and second contact being carried by said sectors and means whereby said sectors may be adjusted simultaneously with a variable degree 65 of movement.

4. A fire control apparatus of the class described which comprises a stabilizable shaft, means for stabilizing said shaft, a sighting 70 telescope carried by said shaft, a pointer rigidly secured to said stabilizable shaft, a pair of coöperating marks for indicating the angle of rolling of a ship, a pair of contact devices for closing a firing circuit, one 75 of said marks and contact devices being rigidly mounted on said pointer, an indicating device mounted adjacent said mark for coöperation therewith, the other of said pair of marks and contact devices being carried by sectors arranged concentrically with a stabilizable shaft, the sector carrying said mark having arranged thereon an indicating apparatus coöperating with the mark and means operatively connecting said sectors 80 for simultaneously adjusting them.

The foregoing specification signed at Essen, Germany, this 16th day of June, 1920.

DR. WALTHER AKEMANN.
